PREPARATION OF PHOSPHATIDES

Ralph A. Marmor and Wendell W. Moyer, Decatur, Ill., assignors to A. E. Staley Manufacturing Company, Decatur, Ill., a corporation of Delaware

No Drawing. Application June 17, 1947,
Serial No. 755,257

3 Claims. (Cl. 260—403)

1

This invention relates to improvements in the preparation of phosphatides from oleaginous materials, particularly to such preparation wherein glyceride oil and phosphatidic material are jointly extracted from the oleaginous material with a liquid solvent, followed by bleaching or decolorizing at low temperature preferably prior to solvent removal.

A primary object of the invention is to improve the color and odor of phosphatides obtained jointly with glyceride oils by extracting oleaginous material therefrom with a solvent for the glyceride oils contained therein.

Another object of the invention is to reduce or eliminate the decolorization of the recovered phosphatides heretofore required to make them acceptable for many uses, chiefly in foodstuffs.

Additional objects of the invention will be apparent from the description and claims that follow.

The invention accordingly comprises the several steps and the relation of one or more of such steps with respect to each of the others thereof, which will be exemplified in the process hereinafter disclosed, and the scope of the application of which will be indicated in the claims.

It is well known that many oleaginous materials, especially those of vegetable origin, contain appreciable proportions of phosphatides, frequently referred to as lecithin. Among these materials are soybeans, cottonseed, corn germs, rape seed, peanuts, and linseed. Attempts have been made heretofore to recover phosphatides from oleaginous materials by extracting the latter with solvents in which the phosphatides are preferentially soluble. Such attempts have not proven satisfactory because the extracted phosphatides were always contaminated with oil, pigments, and other materials which had to be separated from the former at considerable expense.

It is also known that the conventional solvent extraction of glyceride oils from oleaginous material extracts a large part of the phosphatides in the oleaginous material with the oil, and that such jointly extracted phosphatides can be readily coagulated by stirring the oil vigorously with small proportions of water. The ratio of extracted oil to extracted phosphatides is large, usually exceeding 20 to 1. The so-called gum or crude phosphatidic material thus obtained is a hydrosol consisting chiefly of water, oil and phosphatides. Minor constituents frequently present include fatty acids, proteinaceous materials, sterol derivatives, and color bodies. When dried the gum

2

usually contains 60 to 65 per cent phosphatides. At present, this is one of the principal commercial methods for manufacturing phosphatides.

Although large quantities of crude phosphatides are easily and economically manufactured as described above, such material has not found the anticipated application in many potential uses, particularly in foodstuffs, because of its dark color and strong odor. Heretofore, it has been necessary to decolorize and at least partially to deodorize the crude phosphatidic material before it could be satisfactorily used in foodstuffs. Although several conventional methods are available for improving the color and odor of this material, all possess one or more drawbacks with respect to processing time, apparatus required, cost of reagents, and the like.

The objectionable color and odor of crude phosphatides obtained by conventional extraction methods are apparently due to the high temperatures employed to free the extracted oil of solvent. The bulk of the solvent is evaporated from the extract or micella at atmospheric pressure and the remainder is distilled off under reduced pressure, frequently with the aid of injected superheated steam. During the latter operation, the oil is commonly heated to temperatures as high as 100° to 120° C. and held there for substantial periods of time. Prior to this, the oil is also held for considerable periods of time at and above the boiling point of the solvent. In the case of hexane, the solvent most widely used at present, the temperature of prior heating referred to ranges from about 70° to 100° C.

We have discovered that the color and odor of crude phosphatides obtained by extracting oleaginous material with a solvent for glyceride oils and treating the extracted oil with water as described above can be greatly improved by combining low temperature evaporation of solvent from the extract with decolorization either of the oil obtained therefrom. The pronounced beneficial effects of this combination of steps are apparently due in part to preventing a "fixing" or "setting" of the color bodies by the high temperatures conventionally used in evaporating solvent from the micella, and in part to preventing the formation of odorous materials by the heating during solvent removal, the latter materials being independent of color bodies affected by bleaching agents and color adsorbents.

The order in which the solvent is removed and the oil is decolorized does not materially affect the quality of the phosphatides. We prefer to decolorize solution of oil in solvent, either as a

full or partial micella, first, mainly because such solutions are more fluid than the undiluted oil and are therefore more easily percolated or filtered through a bed of the adsorbent material. However, the advantages of this invention also may be obtained by first evaporating the solvent from the micella at low temperature, and then decolorizing the residual oil at suitably low temperature, either in the absence or presence of a diluent.

Any of the color adsorbents and bleaching agents conventionally used for decolorizing glyceride oils are suitable for the practice of our invention. Among the color adsorbents which may be used are activated carbon, magnesia, alumina, and clay, and among the bleaching agents may be mentioned hydrogen peroxide, benzoyl peroxide, chlorine dioxide, and sulfur dioxide. The color adsorbents may be activated by any of the methods well known in the art.

In accordance with this invention, crude phosphatides of markedly superior color and odor can be subsequently obtained from solvent extracted glyceride oils if, prior to refining operations involving temperatures exceeding about 50° C. the oil is treated with a color adsorbent and the solvent is evaporated from the oil, both operations being performed at temperatures not exceeding about 50° C. It is the combination of low temperature solvent removal and color adsorption that is important. As mentioned earlier, the order in which the two steps of the combination are performed does not materially affect the quality of the phosphatides.

In the preferred practice of our invention, the full micella is stirred with a color adsorbent at temperatures not exceeding about 50° C. until color adsorption reaches substantial equilibrium. This usually does not require more than about one hour. Alternatively, the micella may be passed through a bed or column of the adsorbent. The decolorized micella, filtered if necessary, is then distilled under reduced pressure and at a maximum liquid temperature of about 50° C. until no more than about one or two per cent solvent remains in the oil. The vaporized solvent may be recovered by conveying it to an efficient surface condenser. We have observed that evaporation of the last few per cent of solvent from the oil at temperatures not exceeding 50° C. is slow, even though very low pressures be used. It is therefore advantageous to leave about one per cent or so of solvent in the oil. A small proportion of residual solvent does not interfere with coagulation of the phosphatides with an aqueous medium.

The following examples illustrate our invention:

Example 1

Flaked soybeans were extracted in a conventional manner with so-called hexane to provide an extract or full micella comprising about one part soybean oil to three parts hexane. Six liters of this micella was agitated with about 30 grams of an acid activated bleaching clay for about one hour at 25° to 30° C. The clay was filtered from the mixture, and the noticeably decolorized micella was vacuum distilled at a maximum liquid temperature of about 50° C. until the residual oil contained about 2 per cent hexane. The substantially solvent-free oil thus obtained was then stirred vigorously for several minutes at about 50° C. with about 2 per cent of water and allowed to stand until the hydrated phosphatides settled out. This required about four hours. Supernatant oil was decanted from settled phospha-

tides and the latter, together with adhering oil, were transferred to bottles and centrifuged to separate additional adhering oil from the phosphatides. The phosphatidic material thus obtained was much lighter colored and less odorous than conventional preparations.

Example 2

Dried corn germs were substituted for the flaked soybeans in Example 1. The phosphatides thus obtained from the crude solvent extracted corn oil were much lighter colored and of a more pleasant odor than phosphatide obtained by water washing conventional crude solvent extracted corn oil.

Example 3

Substitution of linseed for flaked soybeans in Example 1 yielded the same results with respect to color and odor of the crude phosphatides obtained from the crude oil.

Substitution of activated vegetable carbon, alumina, and magnesia separately for the acid activated clay in the foregoing examples provided phosphatides of similar superior color and odor. The activated carbon, alumina, and magnesia were selected from the types commonly used in the refining of glyceride oils.

Example 4

Flaked soybeans were extracted in a conventional manner with hexane to provide an extract or full micella comprising about one part soybean oil to three parts hexane. Six liters of this micella was stirred for three hours at 50° C. with 10 grams of powdered benzoyl peroxide, then filtered to remove any unreacted peroxide. The filtered and noticeably decolorized micella was vacuum distilled at a maximum liquid temperature until the residual oil contained about 2 per cent hexane. The substantially solvent-free oil thus obtained was then stirred vigorously for several minutes at about 50° C. with about 2 per cent of water and allowed to stand until the hydrated phosphatides settled out. This required about four hours. Supernatant oil was then decanted from the settled phosphatides, and the latter, together with adhering oil, were transferred to bottles and centrifuged to separate additional adhering oil from the phosphatides. The phosphatidic material thus obtained was much lighter colored and less odorous than conventional preparations.

Substitution of dried corn germs for the flaked soybeans in the preceding example resulted in crude phosphatides of equally improved color and odor.

Example 5

Flaked soybeans were extracted in a conventional manner with hexane to provide an extract or full micella comprising about one part soybean oil and three parts hexane. Six liters of this micella was vacuum distilled at a maximum liquid temperature of about 50° C. until the residual oil contained about 2 per cent hexane. This oil was stirred with 30 grams of an acid activated clay for about one hour at 25° to 30° C., filtered to remove the clay, then agitated vigorously with about 2 per cent of water at 50° C. for several minutes, and allowed to stand quietly until the coagulated phosphatides settled out. This required about four hours. Supernatant oil was decanted from the settled phosphatides and the latter, together with adhering oil, were transferred to bottles and centrifuged to separate additional

oil from the phosphatides. The phosphatidic material thus obtained was also markedly superior in color and odor to those qualities of conventional preparations.

If desired, the phosphatides may be coagulated with the aqueous medium at temperatures higher than those employed in the foregoing examples, providing the mixture of oil and coagulated phosphatides is not maintained at the higher temperatures for extended periods of time. For example, coagulation temperatures of 80° to 90° C. are not harmful to the color and odor of the phosphatides if the coagulation is carried out continuously by injecting the required proportion of water into a moving stream of heated oil, agitating the mixture, and then cooling it immediately to about 50° or less.

Also the phosphatides may be coagulated with aqueous solutions of acids, bases, and salts instead of water alone as used in the examples. Use of aqueous solutions of bases is not recommended in the practice of this invention, however, because the phosphatides obtained will be contaminated with the corresponding salts of any free fatty acid present in the crude oil. And if the aqueous solution is a concentrated solution of caustic alkali, such as is commonly used in the alkali refining of glyceride oils, partial saponification of the phosphatides is apt to occur.

Phosphatides manufactured in accordance with this invention have a number of known and potential uses. Among these are reducing the viscosity of chocolate materials, preventing the foaming and spattering of heated margarine, facilitating the wetting of powders and textiles, and improving the quality of lubricating oil.

Any of the solvents conventionally used for the extraction of glyceride oils from oleaginous material may be used in the practice of the invention. The currently preferred solvent is so-called hexane, a high test gasoline boiling over the range of about 63° to 70° C. Other solvents such as trichloroethylene, benzene, and ethanol, all having boiling points under 100° C., have been used.

It is not essential to successful coagulation of phosphatides from solvent extracted glyceride oils with an aqueous medium that all the solvent be evaporated from the oil. The maximum proportion of solvent that may remain with the oil and still permit good coagulation of the phosphatides varies with the kind of solvent. In general, however, as much as 15 to 20 per cent of solvent may be tolerated in the oil from which phosphatides are to be prepared in accordance with this invention.

Since certain changes may be made in carrying out the above process without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

We claim:

1. The process of recovering phosphatides from oleaginous material which comprises extracting the oleaginous material with a solvent selected from the group consisting of hexane, trichloroethylene, benzene and ethanol to pro-

vide an extract containing glyceride oils, phosphatides, and solvent, decolorizing the extract, evaporating solvent from the decolorized extract at a temperature not exceeding about 50° C. to provide a mutual solution of the remaining glyceride oils and phosphatides, agitating said solution with an aqueous medium to coagulate the phosphatides, and separating the coagulated phosphatides from the bulk of the glyceride oils.

5 2. The process of recovering phosphatides from oleaginous material which comprises extracting the oleaginous material with a solvent selected from the group consisting of hexane, trichloroethylene, benzene and ethanol to provide an extract containing glyceride oils, phosphatides, and solvent, evaporating solvent from the extract at a temperature not exceeding about 50° C. to provide a mutual solution of remaining phosphatides and glyceride oils, decolorizing said solution at

10 15 20 25 30 35 40 45 50 55 60

2. The process of recovering phosphatides from oleaginous material which comprises extracting the oleaginous material with a solvent selected from the group consisting of hexane, trichloroethylene, benzene and ethanol to provide an extract containing glyceride oils, phosphatides, and solvent, evaporating solvent from the extract at a temperature not exceeding about 50° C. to provide a mutual solution of remaining phosphatides and glyceride oils, decolorizing said solution at a temperature not exceeding about 50° C., then agitating the decolorized solution with an aqueous medium to coagulate the phosphatides, and separating the coagulated phosphatides from the bulk of the glyceride oils.

3. The process of recovering phosphatides from oleaginous material which comprises extracting the oleaginous material with hexane to provide an extract containing glyceride oils, phosphatides, and hexane, decolorizing the extract, evaporating hexane from the decolorized extract at a temperature not exceeding about 50° C. to provide a mutual solution of the remaining glyceride oils and phosphatides, agitating said solution with an aqueous medium to coagulate the phosphatides, and separating the coagulated phosphatides from the bulk of the glyceride oils.

4. The process of recovering phosphatides from oleaginous material which comprises extracting the oleaginous material with trichloroethylene to provide an extract containing glyceride oils, phosphatides, and trichloroethylene, decolorizing the extract, evaporating trichloroethylene from the decolorized extract at a temperature not exceeding about 50° C. to provide a mutual solution of the remaining glyceride oils and phosphatides, agitating said solution with an aqueous medium to coagulate the phosphatides, and separating the coagulated phosphatides from the bulk of the glyceride oils.

5. The process of recovering phosphatides from oleaginous material which comprises extracting the oleaginous material with benzene to provide an extract containing glyceride oils, phosphatides, and benzene, decolorizing the extract, evaporating benzene from the decolorized extract at a temperature not exceeding about 50° C. to provide a mutual solution of the remaining glyceride oils and phosphatides, agitating said solution with an aqueous medium to coagulate the phosphatides, and separating the coagulated phosphatides from the bulk of the glyceride oils.

6. The process of recovering phosphatides from flaked soybean material which comprises extracting the material with a solvent selected from the group consisting of hexane, trichloroethylene, benzene and ethanol to provide an extract containing soybean oil, phosphatides, and solvent, decolorizing the extract, evaporating solvent from the decolorized extract at a temperature not exceeding about 50° C. to provide a mutual solution of the remaining soybean oil and phosphatides, agitating said solution with an aqueous medium to coagulate the phosphatides, and separating the coagulated phosphatides from the bulk of the soybean oil.

7. The process of recovering phosphatides from linseed material which comprises extracting the material with a solvent selected from the group consisting of hexane, trichloroethylene, benzene and ethanol to provide an extract containing linseed oil, phosphatides, and solvent, decolorizing the extract, evaporating solvent from the decolorized extract at a temperature not exceeding about 50° C. to provide a mutual solution of the remaining linseed oil and phosphatides, agitating said solution with an aqueous medium to coagulate the phosphatides, and separating the coagulated phosphatides from the bulk of the linseed oil.

8. The process of recovering phosphatides from corn germ material which comprises extracting the material with a solvent selected from the group consisting of hexane, trichloroethylene, benzene and ethanol to provide an extract containing corn germ oil, phosphatides, and sol-

10

15

20

vent, decolorizing the extract, evaporating solvent from the decolorized extract at a temperature not exceeding about 50° C. to provide a mutual solution of the remaining corn germ oil and phosphatides, agitating said solution with an aqueous medium to coagulate the phosphatides, and separating the coagulated phosphatides from the bulk of the corn germ oil.
